UNITED STATES PATENT OFFICE

102,451

DESIGN FOR A CAN OR SIMILAR CONTAINER FOR BEVERAGES

Rudolph J. Schaefer, Larchmont, N. Y., assignor to The F. & M. Schaefer Brewing Co., Brooklyn, N. Y., a corporation of New York

Application September 5, 1936, Serial No. 64,732

Term of patent 14 years

To all whom it may concern:

Be it known that I, Rudolph J. Schaefer, a citizen of the United States of America, and resident of Larchmont, Westchester County, New York, have invented a new, original, and ornamental Design for a Can or Similar Container for Beverages, of which the following is a specification, reference being had to the accompanying drawing, forming part thereof.

Figure 1 is a front elevation in perspective of a can or similar container for beverages, showing my new design; and

I claim:—

The ornamental design for a can or similar container for beverages, substantially as shown.

RUDOLPH J. SCHAEFER.
